MINING MACHINE

Charles A. Pratt, Chicago, Ill., assignor to Goodman Manufacturing Company, Chicago, Ill., a corporation of Illinois

Application February 25, 1932, Serial No. 595,054
Renewed December 1, 1933

7 Claims. (Cl. 262—30)

This invention relates to improvements in mining machines and more particularly to improvements in a kerf cutting coal mining machine slideable on its own bottom on the mine bottom 5 while undercutting the coal.

This invention has among other objects to provide a new and improved mining machine of the class described, the parts of which are so arranged as to afford the construction of a low, 10 compact, and simplified machine capable of operating in thin seams of coal where roof supports are spaced close to the coal face. Another object of my invention is to arrange the parts in such a manner that a more efficient motor may be used 15 than formerly has been used on mining machines of the class described due, principally, to the fact that the motor shafts of these prior machines have been rotatable about an axis extending longitudinally of the machine. With such an arrangement it has not been found practical to 20 provide the motor with the usual field coil for each pole. This necessarily restricts the efficiency of the machine and in order to keep the machine to a height which will operate in low coal necessitates the use of a motor of larger 25 longitudinal and transverse dimensions than is desirable. Another object of my invention is to provide a means whereby the motor may be readily accessible, and whereby the armature of said 30 motor may be removed with no vertical movement thereof and very little rearward movement thereof, the motor shell being so arranged that the armature and all of the motor parts may be accessible from one side of the motor instead of 35 from the rearward end thereof.

My invention may be more clearly understood with reference to the accompanying drawings wherein:

Figure 1 is a top plan view of a machine constructed in accordance with my invention mounted on a truck, with parts broken away and in section to more clearly show the details thereof;

Figure 2 is a side elevation of the device shown in Figure 1;

Figure 3 is a sectional view taken substantially on line 3—3 of Figure 1;

Figure 4 is a sectional view taken substantially on line 4—4 of Figure 3;

Figure 5 is a sectional view taken substantially on line 5—5 of Figure 1;

Figure 6 is a sectional view taken substantially on line 6—6 of Figure 1; and

Figure 7 is a sectional view taken substantially on line 7—7 of Figure 1.

Like numerals refer to like parts throughout the various figures.

Referring now in particular to the details shown in the drawings, the embodiment of my invention illustrated comprises a vertically disposed motor 10 slideable on one of its ends on the mine bottom, and a main frame 11 which forms a support and housing for cutting and feeding mechanism extending forwardly of said motor.

A cutter bar 12 projects forwardly from the main frame 11 and is secured to a projection 13 extending forwardly therefrom in a suitable manner not herein shown or described since it is no portion of my invention. The cutter bar 12 is provided with a cutter chain 14 movable thereabout in a usual manner and driven from a cutter chain sprocket 15 freely mounted on the lower end of a vertical shaft 16. The cutter chain sprocket 15 and vertical shaft 16 are driven from the motor 10 in a suitable manner which will 20 hereinafter be more fully described.

Means are provided for moving the mining machine about the mine from working place to working place which may be of any suitable construction, but which means is herein preferably 25 shown as being a track mounted truck 17. The truck 17 is driven from the mining machine motor 10 in a manner which will hereinafter be more fully described for transporting the mining machine about the mine, and is provided with a 30 pivoted forward end so the mining machine may readily be removed therefrom or loaded thereon in a usual manner well known to those skilled in the art.

The main frame 11 is attached to a casing 18 for the motor 10 by means of nuts and bolts indicated at 19 and forms a means for supporting the feeding and cutting mechanism and the drive means therefor. The main frame 11 is so arranged that a passageway is provided for discharging the cuttings from the machine, which passageway is closed to the advance and rearward sides thereof and conforms substantially to the path of the cutter chain 14 for discharging the cuttings to the retreating side of the machine in cooperation with said cutter chain. It should also be noted that the main frame 11 is so arranged that the portion adjacent the advance side of the machine rests directly on the mine bottom and serves as a support for the machine while the portion adjacent the cuttings passageway is raised to form a bottomless passageway for the discharge of the cuttings. This prevents clogging of the cuttings between 35 40 45 50 55

the bottom and top portions of the cuttings passageway in that the cuttings not expelled from the cuttings passageway by the cutter chain 14 are left behind as the mining machine 5 travels along the working face.

Referring now in particular to the motor 10 and motor casing 18, and one of the novel features of my invention, it may be seen with reference to Figure 1 that the motor casing 18 is 10 split diagonally of its length into two halves, herein referred to as a forward half 20 and a rearward half 21. The forward half 20 is bolted to the rearward end of the main frame 11 by means of the nuts and bolts 19, and the two 15 halves are detachably secured together by means of suitable nuts and bolts in a usual manner. The motor 10 is provided with an armature 23 supported on a vertically extending armature shaft 24, and field coils 25, two of which field 20 coils are supported in each half of the casing 18.

With reference to Figures 1 and 3, it may be seen that the motor is so arranged that it is 25 slideable directly on the mine bottom adjacent an end which is adjacent one end of the armature shaft 24. It may also be seen that the armature shaft 24 is supported in suitable bearings which in turn are supported in bearing supports 26 and 27 adjacent its upper and lower ends, respectively. The bearing supports 26 and 27 have 30 a grooved outer periphery which is adapted to be engaged by suitable tongues formed in the forward and rearward halves of the motor casing so the armature 23 may be removed therefrom with no vertical movement thereof. It should 35 be noted that due to the fact that the motor casing is split diagonally, that its rearward half 21 may be removed from the forward half 20 with a minimum amount of rearward movement with respect to the machine. With such an arrangement the armature 23 may be removed from the motor 10 when a breakdown occurs while 40 the cutter bar is sumped under the coal. Thus the motor 10 is arranged so it may be readily accessible in confined spaces and all parts of the motor may be removed therefrom when the 45 machine is at the working face under varying conditions of mining; as, for instance, where the space is very limited as to length and height but where there is ample width, which conditions are common in mines, especially where the 50 roof is poor and it is necessary to space props for supporting the roof close to the working face of the coal.

Referring now in particular to the drive for 55 the feed operating and cutter chain driving mechanism, and several other novel features of my invention, the upper end of the armature shaft 24 has an armature pinion 29 keyed thereto. The armature pinion 29 meshes with and drives an 60 idler gear 30 journaled on its hub in suitable ball bearings supported in a bearing support 31. The idler gear 30 is held in the bearing support 31 by means of a stud 32 integral therewith having a nut threaded on its upper end, and meshes 65 with and drives a spur gear 33 keyed on the upper end of the vertical shaft 16. Said spur gear is journaled on its hub in the bearing support 31 by means of suitable ball bearings of an ordinary construction. The bearing support 31 70 extends longitudinally of the main frame 11 and rearwardly therefrom and its rearward portion rests on the top end of the motor 10. Said bearing support is secured to said main frame by means of suitable cap screws in an ordinary manner, as may be seen with reference to Fig-

ure 3. The bearing support 31 is so arranged that it supports the idler gear 30 and spur gear 33 so said gears may readily be removed for accessibility to parts within the main frame 11 for removing the idler gear 30 from said bearing support and removing said bearing support from the main frame 11.

A worm 34 is cut integral with the vertical shaft 16 and meshes with and drives a worm gear 35 10 keyed on a sleeve 36 freely mounted on a transversely extending shaft 37 for driving feed operating mechanism for the mining machine in a manner which will hereinafter be more fully described.

The cutter chain sprocket 15 is journaled on 15 its hub in the main frame 11 in suitable ball bearings and is provided with a plurality of upwardly extending clutch jaws 38 adapted to be engaged by clutch jaws 39 depending from a clutch member 40 feathered on the vertical shaft 16 for selectively connecting said sprocket with said shaft for driving the cutter chain 14 therefrom.

The clutch member 40 is moved along the vertical shaft 16 by means of a suitable system of levers which may be of any construction, but 25 which are herein preferably shown as comprising a clutch yoke 41 having engagement with said clutch member. The clutch yoke 41 is engaged by a clutch fork 42 keyed on a transversely extending rock shaft 43 supported in the main 30 frame 11 forwardly of the vertical shaft 16 in suitable bearing supports in a usual manner. One end of the transversely extending rock shaft 43 extends beyond the lateral boundaries of the main frame 11 adjacent the advance side thereof 35 and has a hand lever 44 keyed thereto so movement of said hand lever will vertically move the clutch member 40 to engage the clutch jaws 39 with the clutch jaws 38 or disengage said clutch jaws in an obvious manner. Suitable locking 40 means are provided to lock the clutch jaws 39 in an engaged position with or disengaged position from the clutch jaws 38, which means comprises suitable pin and aperture locking 45 means generally indicated by reference character 45.

Referring now in particular to the feeding mechanism and method of operating the same, a feed drum 47 is provided. The feed drum 47 is mounted on a stud 48 for free rotation with 50 respect thereto and has an internal gear 49 keyed to its inner side, which internal gear meshes with and is driven by a spur pinion 50 keyed on the forward end of the transversely extending shaft 37. The transversely extending shaft 55 37 in turn is driven from the motor 10 by means of the worm gear 35, sleeve 36, and a frictionally controlled eccentric reduction device generally indicated at 51, at either a high speed or a lower frictionally controlled speed in a manner which 60 will hereinafter be more fully explained. Said feed drum may thus be rotated at a high speed or a variable low speed controlled by suitable friction means for winding a feed rope 52 thereon and moving the machine along the mine bottom by means of said rope at either a high positioning speed or a plurality of low cutting speeds.

Referring now in particular to the details of the eccentric reduction device 51, a casing 53 70 is journaled within the main frame 11 and rotatably mounted on the sleeve 36. An internal gear 54 is formed integral with a cage 55 and is journaled within the casing 53 for free rotation with respect thereto. An eccentric gear 75

56 meshes with the internal gear 54. The eccentric gear 56 has a lesser number of teeth than the internal gear 54 depending upon the reduction desired and is provided with a plurality 5 of lugs 57, 57 integral therewith and extending outwardly from one of its sides. The lugs 57, 57 have blocks 58, 58 pivotally mounted thereon. The blocks 58 are slidable in guides 59 formed in the casing 53 and disposed perpendicularly 10 with respect to the axis of the transversely extending shaft 37.

It should be noted that the guides 59 are wider than the blocks 58 to permit lateral, as well as longitudinal, movement of said blocks 15 within said guides, the difference in width being dependent upon the difference in teeth between the internal gear 54 and eccentric gear 56.

The eccentric gear 56 is in turn mounted on a suitable bearing 60, herein shown as being a ball bearing of an ordinary construction, which bearing 60 is mounted on an eccentric 61 formed integral with the sleeve 36.

Clutch jaws 63 are provided on the sleeve 36. Likewise, clutch jaws 64 are formed integral 25 with the cage 55. A clutch member 65 is feathered on the transversely extending shaft 37 and extends within the casing 53 and is provided with clutch jaws 66 which may mesh with either the clutch jaws 63 or the clutch jaws 64.

30 Means are provided for retarding rotation of the casing 53 or for allowing said casing to freely rotate with respect to the transversely extending shaft 37, which means herein comprise a friction band 67 engageable with the outer periphery of said casing. A forked member 68 is secured to one end of the friction band 67. The ends of the forked member 68 are engageable with a projection 69 from the main frame 11. A lug 70 is attached to the opposite end of the friction band 67. A rod 71 extends through the lug 70 and has lock nuts 72 threaded to its lower end abutting the lower end of said lug. The rod 71 extends upwardly from the lug 70 through the forked member 68 and projection 69 and has an eye-piece formed on its upper end which has a lever arm 73 pivotally connected thereto. The lever arm 73 is keyed on a transversely extending rock shaft 74, which rock shaft is operated by means of a hand wheel 75 disposed adjacent the rearward end of the machine, and a suitable system of links and levers indicated at 76 in an obvious manner so rotation of said hand wheel in one direction will tighten the friction band 67 against the casing 53 and hold said casing from movement, while rotation of said hand wheel in an opposite direction will permit said casing to rotate with respect to said friction band.

When the eccentric 61 is driven from the motor 10 and the casing 53 is held from rotation by the friction band 67 the eccentric gear 56 will move in an orbital path towards and away from the shaft 37, which path is controlled by the guides 59 and blocks 58 slidable therein.

65 During orbital movement of the eccentric gear 56, a certain number of teeth thereof are continually in mesh with the teeth in the internal gear 54 and each time said eccentric gear completely travels around its orbit, the internal gear 70 54 is moved a distance equal to the width of the number of teeth fully engaged therewith. The speed of rotation of the internal gear 54 is varied by varying the pressure of the friction band 67 on the casing 53, said friction band also acting 75 as a safety device to prevent breakage of the feed

operating mechanism upon overload of the feed drum 47.

The clutch member 65 is shifted along the shaft 37 to engage the clutch jaws 66 with either the clutch jaws 63 or the clutch jaws 64 by means of a suitable system of levers which herein comprise a clutch yoke 79 connected to the clutch member 65 in a usual manner and a clutch fork 80 connected to said clutch yoke. The clutch fork 80 is keyed on a vertically disposed rock 10 shaft 81, which rock shaft is provided with a squared upper end and is adapted to be engaged by a hand lever 82 so movement of said hand lever in one direction or another will move the clutch member 65 in one direction or another. Suitable pin and aperture locking means, indicated at 83, are provided on the hand lever 82 for locking the clutch jaws 66 in a neutral position or in engagement with either the clutch jaws 63 or clutch jaws 64.

20 Thus a means has been provided for driving the feed drum 47 at either a high speed or at lower variable speeds controlled by the friction band 67, which means is of a simplified construction and is so arranged as to safely take care of overloads on said feed drum and prevent breakage of the feed operating parts and take up a minimum amount of space in the machine.

25 Suitable means are provided to retard the rearward end of the mining machine as it is being fed across the coal face by the feed rope 52 and feed drum 47 which may be of any construction, but which herein comprises a retarding drum 84 having a cable 85 wound thereon. The retarding drum 84 is freely mounted on a stud 86 extending rearwardly from the rearward end of the rearward half 21 of the motor casing 18. Means are provided to retard the rotation of the retarding drum 84 and control the paying off of the cable 85 therefrom, which means, as herein shown, comprises a brake band 87 engageable with said drum and operated by means of a suitable hand wheel 88 in an obvious manner.

30 The feed rope 52 may be trained around a sheave 89 adjacent the forward advance side of the machine for feeding said machine across the face during the normal cutting operation, or said feed rope may be trained rearwardly from the feed drum 47 around a sheave 90 disposed adjacent the rearward advance side of the motor casing 18 and around a sheave 91 disposed adjacent the central portion of the motor casing 18 for pulling the mining machine upon the truck 17 in a usual manner, which may be clearly understood with reference to Figure 1. Likewise, a sheave 92 is provided adjacent the rearward retreating side of the machine so the feed rope 52 may be trained therearound for sumping the cutter bar 12 into the coal, or for pulling said machine in a direction opposite to its normal direction of travel.

35 Referring now in particular to the means for driving the truck 17 about the mine, a spur gear 93 is keyed on the hub of the spur gear 33 and meshes with and drives a spur gear 94 on one end of a vertically disposed shaft 95. A bevel pinion 96 is keyed on the opposite end of the vertically disposed shaft 95 and meshes with and drives a bevel gear 97 journaled on its hub in suitable bearing supports secured to the main frame 11 and keyed to a transversely extending shaft 98. The opposite end of the transversely extending shaft 98 is journaled in the main frame 11 and its outer end is flush with the outer end of said main frame. The transversely extending shaft 70 75

- 98 is provided with a squared socket in its outer end which is engageable with a squared coupling pin 99 mounted in the hub of a drive sprocket 100 for slidable movement with respect thereto.
- 5 The drive sprocket 100 is journaled on its hub in a bearing support 101 extending upwardly from the track mounted truck 17. Means are provided for holding the coupling pin 99 in engagement with the squared socket in the transversely 10 extending shaft 98, which means herein comprise a locking member 102 pivotally connected at one of its ends to an arm integral with the bearing support 101 and extending outwardly therefrom around one side of the drive sprocket 100 and 15 having locking engagement with another arm extending outwardly from the bearing support 101 around the opposite side of said drive sprocket. The drive sprocket 100 is connected with forward truck wheels 103 for driving said 20 truck wheels by means of a chain and sprocket drive indicated at 104. The forward and rearward truck wheels are in turn operatively connected together by means of a suitable chain and sprocket drive 105.
- 25 It may thus be seen that when the mining machine has been pulled on the truck 17 by means of the feed rope 52 that the coupling pin 99 may be engaged with the squared socket in the transversely extending shaft 98 for driving the truck 30 17 and moving the mining machine about the mine from working place to working place.

While I have herein shown and described one embodiment of my invention, it will be understood that the construction and arrangement of 35 the various parts may be altered or changed without departing from the spirit or scope thereof. Furthermore, I do not wish to be construed as limiting myself to the specific form illustrated, excepting as it may be limited in the appended 40 claims.

I claim as my invention:

1. In a mining machine, a frame, feeding mechanism therefor comprising a feed drum disposed on one side of said frame for rotation about an 45 axis disposed transversely thereof, cutting mechanism extending forwardly of said frame including a chain carrying cutter bar, and means for driving said feeding and cutting mechanism comprising a motor having an armature shaft rotatable about a vertical axis, said motor including a motor casing 50 slidably directly on the mine bottom and having detachable connection with the rearward end of said frame, said motor casing being split in a vertical plane extending diagonally of said 55 frame and separable to one side of said frame.

2. In a mining machine, a motor having a vertically disposed armature shaft, a casing for said motor engageable directly with the mine bottom, said casing being split diagonally in a vertical 60 plane and the size thereof substantially determining the power producing function of said motor, a frame disposed forwardly of said motor having a projecting cutter bar extending forwardly therefrom, said cutter bar being disposed 65 in planes which intersect said motor, feed operating and controlling means on said mining machine comprising a feed drum disposed adjacent the advance side of said mining machine forwardly of said motor for rotation about a transverse axis, and means for driving said feed drum 70 from said motor at either a high speed or a low frictionally controlled speed comprising a vertical shaft driven by said motor, a worm gear driven therefrom and disposed rearwardly of said vertical shaft, a frictionally controlled gear reduc-

tion device interposed between said worm gear and said feed drum, a shaft coaxial with said frictionally controlled gear reduction means and driven therefrom, and a geared reduction between said shaft and said feed drum.

3. In a mining machine, a frame, a motor having an armature shaft rotatable about a vertical axis, said motor being slidably directly on the mine bottom and being connectible with the rearward end of said frame, cutting mechanism therefor including a projecting cutter bar extending forwardly of said frame and having a cutter chain movable thereabout, feeding mechanism therefor comprising a feed drum having a flexible feeding member adapted to be wound thereon, said feed drum being disposed adjacent the advance side of said frame for rotation about a horizontal axis, and means for selectively driving said feeding and cutting mechanism from said motor comprising a vertically disposed shaft driven from said armature shaft having a cutter chain sprocket freely mounted on its lower end, clutch means for connecting said sprocket with said shaft, a transverse shaft spaced closer to said motor than said vertical shaft, a worm gear coaxial with said shaft and driven by said vertical shaft, a frictionally controlled gear reduction device coaxial therewith, clutch means for operatively connecting said transverse shaft with said frictionally controlled gear reduction device, and a geared connection from said shaft to said feed drum.

4. In a mining machine, a frame, a cutter bar having a cutter chain movable thereabout projecting forwardly of said frame, feed operating means on said frame comprising a feed drum disposed adjacent the advance side of said frame when said mining machine is cutting along a coal face, drive means for said feed drum comprising a vertical shaft, a transversely extending shaft disposed rearwardly of said vertical shaft and driven therefrom, a geared connection from said shaft to said feed drum, and a motor disposed rearwardly of said transversely disposed shaft having a vertical armature shaft operatively connected with said aforementioned vertical shaft, 45 said motor including a motor casing slidably directly on the mine bottom and split in a vertical plane extending diagonally of said frame and separable to one side of said frame.

5. In a mining machine, a frame, a motor having a vertical armature shaft, feeding mechanism therefor comprising a feed drum disposed on one side of said frame for rotation about an axis extending transversely thereof, cutting mechanism projecting forwardly of said frame including a chain carrying cutter bar, means for driving said feeding and cutting mechanism from said motor comprising a vertical shaft spaced forwardly of said armature shaft, a plurality of reduction gears driven from said armature shaft and having driving relation with said vertical shaft, and support means for said gears comprising a bearing member detachably secured to the upper portion of said frame and forming a detachable bearing support for said gears.

6. In a mining machine, a frame, a motor having a vertical armature shaft, feeding mechanism therefor comprising a feed drum disposed on one side of said frame for rotation about an axis extending transversely thereof, cutting mechanism projecting forwardly of said frame including a chain carrying cutter bar, means for driving said feeding and cutting mechanism from said motor comprising a vertical shaft spaced forwardly of said armature shaft, a plurality of reduction gears

driven from said armature shaft and having driving relation with said vertical shaft, and support means for said gears comprising a bearing member having a portion extending rearwardly of said frame adapted to rest on the upper end of the casing for said motor, said bearing member being detachably secured to the upper portion of said frame and forming a detachable support for said gears.

10 7. In a mining machine, a frame, a motor having a vertical armature shaft, feeding mechanism therefor comprising a feed drum disposed on one side of said frame for rotation about an axis extending transversely thereof, cutting mechanism projecting forwardly of said frame including a

chain carrying cutter bar, means for driving said feeding and cutting mechanism from said motor comprising a vertical shaft spaced forwardly of said armature shaft, a plurality of reduction gears driven from said armature shaft and having driving relation with said vertical shaft, and support means for said gears comprising a bearing member extending longitudinally of said frame and having a portion extending rearwardly of said frame adapted to rest on the upper end of the 10 casing of said motor, said bearing member being detachably secured to said frame adjacent the forward and rearward ends thereof and forming a detachable support for said gears.

CHARLES A. PRATT. 15
